UNITED STATES PATENT OFFICE.

FREDERICK E. SCHOOLFIELD, OF COVINGTON, AND JOHN C. OWEN, OF BELLEVUE,
KENTUCKY.

AUTOMATIC RECIPROCATING ELECTROMAGNETIC MOTOR.

1,120,414.

Specification of Letters Patent.

Patented Dec. 8, 1914.

Application filed July 7, 1911. Serial No. 337,247.

To all whom it may concern:

Be it known that we, FREDERICK E. SCHOOLFIELD and JOHN C. OWEN, citizens of the United States, residing at Covington, in the county of Kenton and State of Kentucky, and at Bellevue, in the county of Campbell and State of Kentucky, respectively, have invented certain new and useful Improvements in Automatic Reciprocating 10 Electromagnetic Motors, of which the following is a specification.

Our invention relates to reciprocating electric motors automatically controlled by means of an electric current switched from 15 one stationary magnetic coil to another.

The object of our invention is to construct a simple, inexpensive and efficient electric motor which can readily be attached to rock drills, hammers and the like, to automatically 20 operate same.

Another object of our invention is to produce an electric motor comprising a plurality of solenoids adapted to be energized alternately by means of an automatically 25 controlled switch attached to the machine, and which causes the core or plunger of said solenoids to reciprocate.

Our invention comprises a plurality of solenoids, a core or plunger operating in 30 each solenoid, an arm on said core or plunger adapted to operate the arm of a switch, said switch being adapted to energize and deenergize the solenoids alternately, thereby imparting a reciprocating action to the 35 core or plunger.

Our invention consists more specifically of two magnetizing coils or solenoids wound upon a spool or tube, a plunger inside of said tube or spool, the wires of said solenoids being 40 suitably insulated from said tube, said tube acting as a guide for said plunger, a rigid casing for each solenoid suitably insulated from said coils, a projection from said plunger passing through a slot in said tube, and projecting therefrom between the magnets, a switch arm to which said projection is attached, suitable contact points adapted to be engaged and disengaged by 45 said switch arm, and means whereby said 50 switch arm is reciprocated by means of said

projection on said plunger when the plunger is reciprocated.

In the drawing which serves to illustrate the construction and use of our invention: Figure 1 is a longitudinal section taken 55 through a machine constructed in accordance with our invention, the wire connections being shown in diagrammatic form for the sake of clearness. Fig. 2 is an elevational plan view of the device shown in 60 Fig. 1. Fig. 3 shows our invention applied to a hammering drill or tool.

In the embodiment of our invention as illustrated and which shows a preferred construction adapted to represent the principle 65 of construction and operation, 1 and 2 represent solenoids or coils of a wire which are suitably insulated, wound upon a tube 3, and suitably insulated therefrom. A cylindrical casing 4 is suitably provided and incloses 70 said solenoids, and end plates 5 and 6 are fastened to said cylindrical casing 4 at each end, thus providing two solenoids, A and B. A core or plunger 7 is provided, and is adapted to reciprocate inside of said tube 3. 75

A tool holder 32 of non-magnetic material at one end of the tube is provided with a head 33 against which the plunger 7 is adapted to strike impinging blows. A buffer spring 9 is provided between the head 33 of 80 the tool holder 32 and end plate 6 of the solenoid. Another buffer spring 8 is provided at the other extreme end of and within the tube 3 against which the plunger 7 is adapted to strike at the end of its return 85 stroke.

The tool holder 32 is provided with a suitable socket 11 (shown in dotted lines in Fig. 1 and in full lines in Fig. 2) for the purpose of connecting said tool holder or 90 plunger to a rock drill or hammer adapted to be driven thereby. The plunger or core may be made up of three sections 7^a, 7^b and 7^c, as shown in Fig. 1, the two end sections being made of magnetic material while the 95 middle section may be made of non-magnetic material. Thus the magnetism of each solenoid will draw in the plunger to a point where the center of the magnetic action of the plunger at the same end coincides with 100

the center of the solenoid, and in this way the retarding force would be sufficient to limit the stroke of the plunger. The length of the magnetic cores could be adjusted 5 properly to eliminate the buffer springs 8 and 9, but, however, it is preferable to use the buffer springs also.

Fastened to the plunger 7 is an upright projection or operating rod 12, which is 10 adapted to reciprocate with said plunger 7. A switch arm 13 is mounted in a suitable manner upon the top of the casings for the magnets by means of screws 14 which pass through elongated slots 15 in the switch arm 15 13. The projection or operating rod 12 passes through a slot 16 in the switch arm 13.

Mounted on the ends of the switch arm 13 are contact fingers 17 and 18 which are 20 adapted to connect to contacts 19 and 20 fastened on the casings 4 of the solenoids A and B respectively. The switch arm 13 is 25 preferably constructed of insulating material, and is preferably mounted upon blocks of insulating material in order to thoroughly insulate the contact fingers 17 and 18 from the casing of the magnets A and B.

It will be understood that while we have 30 shown and described a particular form of switch, we do not wish to be understood to limit ourselves to the particular form of 35 switch shown. We have simply constructed and described this form of switch to illustrate more clearly the principle of the operation. Other forms of switches could of course readily be applied.

The operation of the device is as follows: The current passes through wire 21 to wire 40 22 as shown by the connection 23. The wire 22 is connected to the contact finger 17 on the switch arm 13. The current then passes 45 through the contact finger 17 to the stationary contact 19 suitably insulated from the casing of the solenoid A. From the contact 19 the current passes through the wire 24 which is connected to the coils of the 50 magnet B, as shown. When the current passes through the coils of the solenoid B, it immediately energizes said solenoid and draws the core of plunger 7 into said solenoid B quickly and with considerable force, 55 thereby imparting motion to the end of the tool holder 32 and to whatever it may be connected. The other end of the coil in the solenoid B is connected to wire 25, to which 60 is connected at 26 the wire 27, which is the return wire of the circuit. Thus a complete 65 circuit is formed. Now when the plunger 7 has been drawn into the solenoid B the upwardly extending projection or operating 70 rod 12 is drawn with said plunger, and upon reaching the end of the slot 16, draws said switch arm 13 along with it until it has 75 broken the connection between the finger 17 and the stationary contact 19 on the sole-

noid A. Upon breaking the circuit at this 80 point, it immediately makes a connection between the contact finger 18 and the stationary contact 20 upon the solenoid B. As soon as this connection is made, the current which passes in through wire 21 flows through the 85 wire 22 to the finger 18 instead of the finger 17, and through the stationary contact 20 to wire 28. The wire 28 is connected to the coil 1 of the solenoid A, and thereby energizes the solenoid A which immediately draws the 90 plunger back into the solenoid A, the current passing from said solenoid A to the wire 25 and thence to the wire 27 as before. As the plunger 7 is returned, the operating rod 12 reaches the other end of the slot 16 in 95 the switch arm 13, and connects the contact finger 17 and the stationary contact 19 together, as before, and this operation is continuously repeated, thus automatically energizing the solenoids A and B alternately, 100 and imparting a reciprocating motion to the plunger 7, thereby operating whatever it is found desirable to operate by said plunger 7. In Fig. 3 we show the plunger directly connected to a hammer tool which may be of 105 any desired type. The solenoids A and B are suitably mounted in the casing 29 of the hammer tool and the core 7 is suitably coupled at 31 to the tool 30, thereby imparting a reciprocating movement thereto.

Our device can readily be modified in construction without departing from its spirit and scope, and we do not wish to be confined to the exact details of construction shown.

We claim:

In combination with two solenoids and supporting means therefor and a plunger lying within the fields of both of them and rectilinearly reciprocated by them as they 105 are alternately energized, a switch comprising a bar and mountings for said bar on the supporting means of the solenoids whereby said bar lies parallel with said plunger and is movable parallel with said 110 plunger but to a lesser extent, said bar having engaging means spaced apart longitudinally thereof, and engaging means extending from said plunger to cooperate with the engaging means of the bar, the engaging 115 means of the bar being spaced apart longitudinally of the bar such distance with respect to the reciprocation of the plunger and the dimension of the engaging means of the plunger that said bar is reciprocated through 120 its lesser extent of reciprocation during and in the same direction as each reciprocation of the plunger, contact means carried by the respective ends of the bar and electrically connected together, the mounting of said bar 125 comprising means insulating it from the supporting means of the solenoids, and contact means carried upon and insulated from

the supporting means of the solenoids and
insulated from each other, with which the
respective contact means on the bar make al-
ternate contacts upon the reciprocation of
5 the bar, this latter contact means being con-
nected respectively to the conductor of the
opposite solenoid whereby said switch is
adapted to automatically control the current

supplied to the respective solenoid to effect
said reciprocation of said plunger.
